UNITED STATES PATENT OFFICE.

PATRICK MCENTEE, OF MONTGOMERY, MINNESOTA.

CAR-COUPING.

SPECIFICATION forming part of Letters Patent No. 413,727, dated October 29, 1889.

Application filed September 21, 1888. Serial No. 286,053. (No model.)

To all whom it may concern:

Be it known that I, PATRICK MCENTEE, a citizen of the United States, residing at Montgomery, in the county of Le Sueur and State of Minnesota, have invented certain new and useful Improvements in Car-Couplings; and I do hereby declare that the following is a full, clear, and exact description of the same, reference being had to the accompanying drawings.

10 The object of the invention is to enable the coupling and uncoupling of cars provided with the ordinary links and pins to be done from the sides or top of the cars.

15 The invention, generally stated, consists in a quadrantal frame pivoted to the end of the car and connected by a chain to the coupling-pin and provided with levers operated from the sides or top of the car to raise the pin out of the link or insert it.

20 The invention is illustrated in the accompanying drawings, in which—

25 Figure 1 represents an end view of a car provided with my improvements. Fig. 2 is a side view of the same, showing the pin in position in the draw-head. Fig. 3 shows the same, the pin being withdrawn from the link. Figs. 4 and 5 are details of the quadrantal frame; and Figs. 6 to 9 are modifications thereof, to be hereinafter fully explained.

30 A in said drawings represents a freight-car, B the draw-head, and C the coupling-pin, of the usual construction.

35 D is a rod held in horizontal position on the end of the car by staples *a*, that permit the rod to turn, and also allow it slight play toward and from the car. The middle portion *d* of the rod is bent into quadrantal shape, and to its outer curved side is attached a relatively wide sheet-metal plate *e* by bending on 40 the rod the tongues *e'*, formed in the plate at opposite sides of its median line. An eye *d'* is formed at the outer angle of the frame by a loop in the rod *D*, and to this eye is attached a chain *f*, carrying on its lower end an angle-iron frame *g*. The horizontal portion of the frame *g* has an opening suitable for engaging the head of a coupling-pin *C*. The pin is introduced through this opening into the draw-head and link. The ends of the rod *D* are 45 bent at the sides of the car at right angles to form cranks *D²*, by means of which the rod can be given a partial rotation, and a lifting-

lever *h*, having a handle *h'* at the top of the car, is connected at its lower end to an arm projecting at an angle of about forty-five degrees 55 downward from the rod *D*. This arm *D'* may be formed by bending the rod itself, as shown. The arrangement of the several parts should be such that when either of the cranks *D²* or the lever *h* is operated to partially rotate the 60 rod *D* the quadrantal frame *d* will be given a quarter-turn, and in its upward rotation will constantly draw the chain *f* in vertical direction by reason of the contact of the chain with the curved surface of the plate *e*, and so that 65 when the limit of movement has been reached the pin *C* will have been freed from the link, but have its point still within the upper portion of the draw-head. Thus a coupling can be made by operating a lever at the top or side 70 of the car to lift the coupling-pin and hold it in position to descend by gravity into the link when the latter has entered the draw-head and the operator releases the lever.

75 In the modified construction illustrated in Figs. 6 and 7 the sheet-metal plate *e* is dispensed with and a sufficiently broad contact-surface afforded on the quadrantal frame for the chain *f* by bending the middle portion of the rod *D* into zigzags *d²*, and also suitably 80 bending this portion to form a quadrant-shaped frame.

In Figs. 8 and 9 are shown a quadrantal frame *K*, of metal, over which the middle portion of the rod *D* may be bent and embedded 85 in a groove *k*, extending entirely around the frame. An eye *l* is provided for attaching the chain *f*, and lateral flanges *i* along the curved portion serve as a substitute for the sheet-metal piece *e* in affording a bearing-surface 90 for the chain while the frame is being rocked. A lip *k'* on the frame *K* at the point of crossing of the two portions of the rod holds them in place when they have been bent to their final shape.

95 Having described my invention, what I claim, and desire to secure by Letters Patent, is—

1. In a car-coupling device, the combination, with a rocking rod and a segmental frame carrying a chain on its face, of the slotted angle-iron for engaging the head of a coupling-pin, substantially as set forth.
2. In a car-coupling, a quadrantal frame

carried by a rocking rod that is provided with a lateral arm, cranks at the sides of the car, and a rod extending from said arm to the top of the car for operating said rocking rod, a chain attached to said frame and engaged by the curved surface thereof, and an angle-iron carried by the chain for engaging the head of a coupling-pin, substantially as set forth.

3. A car-coupling device consisting of a rocking rod bent at its middle to form a quadrantal frame at right angles thereto, and bent also at one side of the middle to form an arm, cranks on the ends of the rod, and a vertical lever connected to said arm, a curved plate se-

cured to the arc of said frame, and a chain secured to its outer angle for raising and lowering a coupling-pin, substantially as set forth.

4. In a car-coupling device, a horizontal rocking rod bent at its middle to form a quadrantal frame at right angles thereto and the arc of such frame provided with lateral bends adapting it to serve as a bearing-surface for a chain, substantially as set forth.

PATRICK MCENTEE.
